United States Patent Office.

CHARLES A. REIGHT, OF MIDDLETOWN, NEW YORK, ASSIGNOR TO HIMSELF, HENRY B. DILL, AND GEORGE A. SWALM, OF SAME PLACE.

Letters Patent No. 77,092, dated April 21, 1868.

IMPROVEMENT IN MILK-CANS.

The Schedule referred to in these Letters Patent and making part of the same.

TO ALL WHOM IT MAY CONCERN:

Be it known that I, CHARLES A. REIGHT, of Middletown, in the county of Orange, and State of New York, have invented a new and improved Milk-Can; and I do hereby declare that the following is a full, clear, and exact description thereof, which will enable others skilled in the art to make and use the same, reference being had to the accompanying drawing forming part of this specification.

The object of this invention is to provide milk-cans, which shall be sufficiently strong to sustain the rough usage encountered during transportation by rail or otherwise, without becoming injured, and which shall not exceed a reasonable limit as to cost.

This object has been attempted in many ways, but the most satisfactory seems to have been to form the cylindrical part of the can, as shown at A, of sheet iron, (about the quality No. 16, more or less,) but heretofore a thoroughly satisfactory result has not been obtained, as, from the thickness of the sheet iron, it could not be double-seamed with the top, C, and bottom, E, owing to the greater thickness of the iron.

The common tin of commerce is sufficiently strong for the top and bottom of the can, but when soldered to the iron, as heretofore done, it was frequently broken away from the iron at the seam, by the rough handling which they usually receive from railway-employees.

In order to obtain a stronger junction of the top and bottom of the can with the iron cylindrical part of the same, I unite a band of tin, B, similar to the tin of the top and bottom, to each top and bottom by a double-seam, as shown in the accompanying drawing, and solder these tin bands to the iron cylinder A, on the inside of the same, by the curved soldering-irons well known to the trade. For additional security, I rivet the bands to the iron, as shown at a, &c.

The formation of the double seam causes the bands B to be less in diameter than the cylinder A, and it would not then come in close contact with the said cylinder in a manner suitable for soldering, without being upset or rimmed, as shown at b, which operation is performed with a proper tool.

Thus, by my invention, I accomplish the uniting of the three aforesaid parts of a trade milk-can with a strong joint, which, from its strength and even exterior, is not liable to become ruptured by the most violent usage to which such cans are subjected.

E is the ordinary removable cap of the can, and D the iron band used to strengthen the base-flange of the same, also commonly used.

Having described my invention, I claim as new, and desire to secure by Letters Patent—

The combination of the tin band B, double-seamed, with the tin top or bottom of a milk-can, and soldered or riveted to the iron cylinder A, of greater thickness than the said bands, or top or bottom, all substantially as and for the purpose shewn and described.

CHARLES A. REIGHT.
